METHOD FOR RESTORING DEFORMED
SHEET METAL SURFACESPerry R. Roper, South Gate, Calif., assignor to
Anthony Oberholtz, Los Angeles, Calif.

Application February 3, 1951, Serial No. 209,216

2 Claims. (Cl. 29—148)

1

This invention relates to improvements in metal working equipment and methods, and is especially concerned with the art of repairing and restoring original contours of metal forms such as relatively thin vehicle body sections, fenders, and similar parts which have become dented or otherwise damaged in collisions or the like.

Until development of the present invention repair processes and equipment for this purpose have been generally limited to certain well-known systems and tool combinations, such as those utilizing smooth weighted tough-faced steel dolly block elements of various straight and/or curved shapes adapted to be held under and in juxtaposition with the metal bodies being worked upon, and conforming substantially to the original contour of such bodies, while co-operating hammer blows are struck against the outer or exposed dented surface of the damaged body at a location directly opposite the dolly-block so as to compress the dented portion of the damaged metal and force the same back as nearly as possible into original position, the usual finishing operations being thereafter employed, which may include the use of a pick-hammer (the striking head of which is in the form of an elongated narrow projection terminating in a rounded point of a size capable of working rather minute areas of damaged metal) which hammer is lightly applied from underneath the indented metal so as to bring any remaining minute depressed areas outward beyond the general periphery of the original contour in order that they may be filed or ground down to bring about a satisfactory reforming of the outer surface of the damaged metal by restoring a perfectly smooth surface before re-painting.

The repairman usually encounters considerable difficulty in attempting to re-shape the damaged metal by the above well known and generally used process while using the tool equipment of the prior art, because the body metal often becomes stretched and springy when dented and will not readily bend back into desired shape, and must therefore be carefully and painstakingly worked for a long period of time with heat, hammer, and other equipment in order to avoid creasing, undue weakening, or perforation before any improvement becomes noticeable. Pounding the metal between a heavy flat steel hammer-head and the ordinary smooth weighted dolly-block in the usual fashion tends to further deform the metal by spreading, thinning, and warping and has the effect of creating additional "crown" when the metal flexes outward

2

toward the operator, making the same increasingly difficult to control. When a shrinking-hammer is used to localize and straighten the damaged metal against the anvil-like hard smooth backing-face of the ordinary dolly-block there is a tendency on the part of the struck area to crimp or buckle under the heavy force of the hammer blows, and it sometimes becomes perforate under such conditions, making progress all the more difficult.

10 In the use of pick-hammers the usual procedure is to alternately drive rather minute dented portions of metal upward or outward from the under side of the metal in the direction of the workman, and then lightly file the area of the dent on the workman's side of the metal, thus brightening the raised areas so that the portions still remaining somewhat depressed and out of line will be clearly revealed as contrastingly dark or dull among the file-brightened high spots. This process is continued progressively until the general contour is satisfactorily re-established, which latter condition will be revealed when the entire area worked upon ultimately becomes uniformly bright under action of the file or grinding device.

15 Since a pick-hammer has only a single working point, many light blows must be struck with it, usually upward or outward in the direction of the repairman, in a totally concealed location, against the damaged area, which requires much time to work a given relatively small area of metal in order to make the desired progress. Moreover, it is difficult to apply a pick-hammer 20 properly against a particular point from underneath the damaged metal because of the usual lack of space in which to swing such a hammer between adjacently located and sometimes entirely concealed body parts, so sometimes it becomes preferable or necessary to effect total removal of the part damaged for purposes of more convenient repair, which, however, involves considerable disassembly time. The pick-hammer's 25 efficient manipulation requires considerable skill to be effective, while its careless or improper use could easily result in the metal becoming unduly and un-uniformly raised to a degree that extreme thinning and weakening, or possibly even perforation, might occur at the time of striking the pick-hammer blow or at the time of filing the metal down if undue or uneven force is applied thereagainst. Under such conditions the addition of further metal by brazing or welding to 30 reinforce the damaged area and to restore its proper contour and proportions prior to re-paint-

ing, must often be resorted to, adding substantially to the cost of the repair job.

It is the primary object of the present invention to provide new and novel tool equipment and repair methods which, when used in doing the repair jobs aforementioned, will greatly simplify the procedure, dispense to a very considerable degree, if not entirely, with certain tool manipulations heretofore requiring extremely expert services, and therefore enable a relatively inexperienced operator to perform the work involved satisfactorily and conveniently with the aid of but a minimum amount of easily handled equipment, and with a minimum amount of time and labor, at the same time generally overcoming the problems above referred to.

It is also an important object of the invention to provide a new and novel tool and repair system for the general purposes above set forth, which will enable the operator to dispense with the use of a pick-hammer in many instances, yet enable him to perform the operations formerly requiring such pick-hammer just as expertly and in less time than was heretofore required.

A still further object of the invention is to make possible the extended use of a relatively soft-faced flat-head hammer in re-forming relatively thin sheet metal areas in operations where the same could not heretofore be effectively employed because of the type of co-operating equipment available for such purposes.

Another and further important object of the invention is to provide a tool unit of novel design which, when used in combination or co-operation with a conventional type of hammer of given size, creates a unique thin-metal repair system which is more efficient in operation and in results obtained than methods heretofore used for the same purpose, and incidentally extends to a very considerable degree the field of use of such conventional type hammer, so that the use of a multiplicity of hammers of different sizes as well as certain other equipment, can hereafter be dispensed with in given operations.

A further object of the invention is to provide a new and novel form of easily handled dolly-block used as a combined backing and forming element in repairing dented objects made of relatively thin metal, which dolly-block shall be adapted to perform the same general backing function as an old-type dolly block while at the same time possessing inherent properties rendering it capable of simultaneously, conveniently, and efficiently performing additional functions heretofore requiring the use of two or more separate tools which were extremely difficult to handle while doing the same class of work.

Another and still further object of the invention is to provide a system of easily manipulated labor-saving co-operating tools utilizing a new device of novel design for re-forming dented metal, which system and equipment, insofar as the action created and results obtained by use thereof, combines the working principles, functions, and advantages of, and now to a considerable extent replaces, such old-type conventional equipment as the pick-hammer, the smooth-faced dolly-block, the shrinking hammer, and certain other devices heretofore considered essential for performing certain repair operations, while at the same time also eliminating a substantial portion of the overall weight of the tools and equipment involved, yet enabling the workman to produce equally expert results most economically and in a minimum of time.

Other and further objects of the invention will be apparent from the disclosures in the accompanying drawings and following specification.

The invention, in a preferred form, is illustrated in the drawings and hereinafter more fully described.

In the drawings:

Figure 1 is an elevation of a metal repair dolly for general use, made in accordance with the present invention.

Figure 2 is a sectional view of the same dolly taken on the line 2-2 of Figure 1.

Figure 3 is a view similar to Figure 1 showing the opposite side of the same dolly.

Figure 4 is an end view of the same dolly showing the specially formed fender-flange contacting portion thereof.

Figure 5 is another end view of the same dolly showing the opposite end portion thereof.

Figure 6 is a pictorial view illustrating the preferred manner of use of the same dolly during a fender-dent repair operation, while employed in co-operation with a metal-working hammer according to the novel repair system of the invention.

Figure 7 is an enlarged fragmentary sectional view showing in more detail the novel metal-working process depicted in Figure 6.

Figure 8 is a view similar to Figure 7 illustrating the effect of a blow delivered by a yieldable face hammer upon the fender-dent area during a pre-finishing operation when the improved dolly element of this invention is used as the backing element in the process.

As shown in the drawings:

Reference is had to Figures 1 to 5, inclusive of the drawings, illustrating in detail the unique and novel dolly-block 10 forming part of my invention, which dolly-block is a solid unitary body made of any suitable metal providing the desired weight and toughness, with one or more suitably contoured metal working contact surfaces 11, 12, each having many contiguous tiny pyramid-like raised teeth or similar projections 13 whose somewhat pointed apices are arranged substantially on a common plane according to the straight or curved lines comprising the dolly-block's special design or contour, which is adapted to conform substantially to the inner, under, or other concealed portions of a relatively thin automobile fender 14 or similar body part which it is adapted to be held against during a repair operation.

The narrow sides 15, 16, of the dolly-block 10 are left relatively smooth and are adapted to be gripped between the fingers of the workman, preferably in the manner shown in Figure 6. One end of the dolly-block 10 may be formed with an integral longitudinal extension 17 somewhat narrower than the main body portion of the dolly-block, one face of said extension being a continuation of the metal-working surface 12, its opposite side being arcuately or otherwise cut out as shown at 18, the said extension 17 being adapted to slidably rest in the channel 19 created by the normally in-turned edge 20 of the metal job element 14 being worked upon, whenever such in-turned edge is provided and whenever the damaged area is located near the edge 20 of the metal body 14, the extreme end of the projecting extension 17 being also preferably contoured so as to conform substantially to the shape of the in-turned metal 20, so that the workman can conveniently and with practically no effort slide the dolly-block 10 along the surface of the body 14 while the block is performing its backing function in co-operation with the hammer strokes

being simultaneously struck against the opposite side of the job metal 14 by the operator in following the course of the dolly-block 10 as best shown in Figures 6 and 7. This feature also permits the workman to otherwise temporarily relieve himself of the block's substantial weight while maintaining the tool 10 in position adjacent the work area between hammer strokes or during momentary rest periods, and the supported sliding motion permitted during operations enables the operator to more easily accomplish work along the edge 20 in a more uniform fashion than heretofore.

The edge portions of the dolly-block 10 are preferably rounded off somewhat to eliminate sharp edges so that the workman may be able to obtain a comfortable grip upon the device, the projections near the corners or edges being accordingly more or less flattened at such locations so as to gradually taper downward toward and merge with the surface of the block's sides 15, 16.

The teeth or projections 13 on surfaces 11 or 12 are knurls and their uniform arrangement forms said surfaces into knurled faces, the same being working faces of the block 10.

In performing a metal-straightening operation of the kind above referred to my dolly-block 10 is held against the dented area 14' in the same manner as the old type dolly-blocks, as best shown in Figures 6 and 7, and when used in co-operation with relatively light blows struck by the hammer 21 in the fashion indicated, will tend to prevent undue spreading and other objectionable deforming of the job metal 14 by reason of relatively uniform frictional or biting contact of the numerous projections 13 with the said job metal, simultaneously producing relatively uniform outwardly directed excrescences over a substantial area of the damaged surface to the extent desired and under a minimum of impact shock.

After the job metal 14 has been restored to substantially its normal initial condition, practically all stretch that may have been imparted thereto is absorbed in the mentioned excrescences (more particularly shown in Fig. 8). By filing, grinding or by other known methods, these excrescences are removed and the outer surface of the job metal rendered smooth.

My improved tool 10 is preferably used to back blows struck by a relatively large-faced hammer or mallet of the "soft" or yieldable variety, such as those made of wood, fibre, rubber, or soft metal, capable of providing the desired striking force. By the use of such preferred hammer equipment it is possible to keep the shock of the impact at a minimum and at the same time provide a co-operating yieldable surface into which the raised metal points may become directed, as best shown in Figure 8, thus tending to prevent any forging or perforation thereof and preserving the original characteristics of the worked metal.

Thus the tool 10, by producing the same action as a plurality of simultaneous pick-hammer blows (each projection 13 functioning in the capacity of a separate pick-hammer), completely replaces the pick-hammer in this particular phase of the repair operation, while also re-contouring the body metal 14 in an obvious manner by reason of its appropriately designed general shape, which is adapted to conform substantially to the normal lines of the said body metal. Since the use of a pick-hammer is completely eliminated in most instances due to the substi-

tution of my relatively thin toothed dolly-block, which is easily manipulated in cramped quarters, the complete removal of the damaged part under such conditions for convenience in making repairs, is no longer necessary in most cases.

The use of my improved form of dolly-block also permits the workman to deliver a normal but more effective hammer blow over the damaged area of the body metal with the unique 10 result of properly re-forming the metal quickly and with much less effort than heretofore, in a manner tending to preserve the metal's original form and characteristics by materially reducing if not entirely eliminating the forging and thinning action formerly inevitable when using the old methods and equipment.

Furthermore, my new system and equipment permits the use of a broader-faced hammer of any suitable or preferred diameter for most rapidly and effectively delivering the required force over a much larger portion of the damaged area than was practicable by use of the old methods and equipment, and with but a minimum number of blows, so as to make more rapid 20 progress possible, since substantially the entire face area 11 or 12 is instantly responsive to the force of a single hammer blow, depending upon the dimensions of the striking face of the hammer used, all projections 13 within the radius 25 of the hammer face being capable of simultaneously reacting to each hammer blow according to the amount of force applied and the shape of the damaged part relative to the tools referred to. Heretofore it has been considered necessary 30 to use only small-headed hard-faced hammers for this particular type of repair operation against the backing action of the old type smooth-faced dolly block. Consequently the task was a tedious one, and slow and uncertain of 35 results. The use of broad-faced hammers was deemed impracticable because of the well known tendency of the body metal to further deform, crimp, or buckle under the blows of the broad-faced instrument, which possibility is eliminated 40 when my improved form of dolly-block is used.

By the use of my new and improved system the use of the referred to "soft" or yieldable-face hammers, as well as the metal type broad-faced hammer, is very considerably extended 45 to operations wherein they were not formerly considered adaptable or practical, and, as is perfectly obvious from the foregoing discussion, the number of tools required for performing a given job is thereby very materially reduced. Since 50 the dolly-block element 10 simultaneously performs the functions of both pick-hammer and contouring device, only a co-operating hammer of suitable type is ordinarily required in combination with such dolly-block element for pursuing the work at the stage mentioned, eliminating much lost time formerly experienced by 55 the workman when constantly picking up and laying down in alternate fashion the more numerous tools ordinarily used under the old repair methods.

Furthermore, since the numerous projections 13 of my dolly-block element automatically locate the so-called "low spots" or dents of the damaged metal 14 from the usually concealed 60 location when held in position thereagainst in the general area of the dents as best shown in Figure 7, the formerly required special technique developed by the expert pick-hammer user under the old system of locating such "low spots" by 65 means of alternate filing and pick-hammer blows,

is no longer essential, enabling the most inexperienced workman to satisfactorily make the referred to repairs when using my improved dolly-block according to the novel system herein disclosed, in a very minimum of time.

Also, inasmuch as the use of a filing tool is greatly reduced if not completely dispensed with by the provision of my speedy and effective new metal working system above described, a very substantial amount of working time is saved on each job and the major cause of metal weakening during repair is thereby removed, at the same time also doing away with one of the most laborious, unpleasant, and metal-wasting operations.

I am aware that many changes may be made and numerous details of construction varied throughout a wide range without departing from the principles of the invention.

I claim as my invention:

1. A method for re-forming a deformed and stretched area of a thin metal member, said method consisting of restoring the deformed area to substantially its normal position while simultaneously with such restoration embodying the stretch in said area in a multiplicity of outwardly directed excrescences that are shallower than the thickness of the metal member, and then removing said excrescences to smoothen the outer surface of said member.

2. A method for restoring a deformed area of a thin normally curved metal section that consists in progressively reducing the degree of deformation of said area by repeated hammering

13
5

on the outer side of the deformed area with a tool substantially softer than the metal of the section while backing the inner convex side of the deformed area with a tool harder than the metal of the section to restore the deformed area to approximately its initial condition while the harder tool forms in the deformed area a multiplicity of outwardly directed indentations that are concave on the convex side of the deformation and convex on the concave side, and thereafter removing the convex excrescences of said indentations to, thereby, smoothen the exposed normally curved surface of the restored area.
